CLAIM

The ornamental design for a gaming machine with rotating dice, as shown and described.

DESCRIPTION

FIG. 1 is a perspective view of a gaming machine with rotating dice showing the new design;

FIG. 2 is a front view thereof;

FIG. 3 is a right side view thereof;

FIG. 4 is a left side view thereof;

FIG. 5 is a top view thereof; and,

FIG. 6 is an enlarged perspective view thereof.

In these drawings, the solid lines illustrate the claimed ornamental design, whereas broken lines illustrate unclaimed environmental features and form no part of the claimed design. The jagged lines shown in broken lines in FIG. 6 are to show the enlarged portions and form no part of the claimed design.

1 Claim, 6 Drawing Sheets
